UNITED STATES PATENT OFFICE.

SAMUEL HELLER, OF NEW YORK, N. Y.

DESIGN FOR A PRECIOUS, SEMIPRECIOUS OR SYNTHETIC STONE, OR AN IMITATION THEREOF.

49,305.

Specification for Design.

Patented July 4, 1916.

Application filed March 2, 1916. Serial No. 81,758. Term of patent 7 years.

To all whom it may concern:

Be it known that I, SAMUEL HELLER, a citizen of the United States, residing at the borough of Manhattan, in the city, county, and State of New York, have invented a new, original, and ornamental Design for a Precious, Semiprecious or Synthetic Stone, or an Imitation Thereof, of which the following is a specification, reference being had therein to the accompanying drawings, which form a part thereof.

In the drawings:—Figure 1 is a plan view of a cut stone embodying my design; and Fig. 2 is a side view thereof.

I claim:—

An ornamental design for a precious, or a semi-precious or a synthetic stone or an

imitation thereof, consisting of a crown having a substantially circular girdle and embodying therein a square flat table, four triangular facets, the base of each of which is at said table and the apex of each of which is at said girdle, each of said triangular facets having at each side thereof a substantially trapezoidal facet having one side thereof at the girdle and a substantially triangular facet at one side of each of said trapezoidal facets with one side thereof at the girdle, and a pavilion having facets thereon.

SAMUEL HELLER.
